Primary Examiner — Austin Murphy(74) *Attorney, Agent, or Firm* — Davis Wright Tremaine LLP; George C. Rondeau, Jr.(57) **CLAIM**

The ornamental design for a communication outlet, as shown and described.

DESCRIPTION

FIG. 1 is a top rear perspective view of a communication outlet showing our new design;

FIG. 2 is a top front perspective view thereof;

FIG. 3 is a rear view thereof;

FIG. 4 is a right side view thereof;

FIG. 5 is a top plan view thereof;

FIG. 6 is a left side view thereof;

FIG. 7 is a bottom plan view thereof; and,

FIG. 8 is a front view thereof.

The broken lines represent portions of the communication outlet that form no part of the claim.
